UNITED STATES PATENT OFFICE.

STEPHEN B. NOWAK, OF BUFFALO, NEW YORK.

DESIGN FOR A DIRECTION SIGNAL.

Application filed April 14, 1922. Serial No. 1,767. Term of patent 14 years.

To all whom it may concern:

Be it known that I, STEPHEN B. NOWAK, a citizen of the United States, residing at Buffalo, in the county of Erie and State of New York, have invented a new, original, and ornamental Design for Direction Signals, of which the following is a specification, reference being had to the accompanying drawings, which form a part thereof, and in which—

Figure 1 is a front elevation of a direction signal, showing my new design; and Figure 2 is a side elevation thereof.

I claim:
The ornamental design for a direction signal, as shown.

STEPHEN B. NOWAK.
